UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

ANTIFRICTION SIDE BEARING

Application filed May 12, 1928. Serial No. 277,268.

This invention relates to improvements in anti-friction side bearings.

The main object of the invention is to provide a side bearing for railway cars, co-operating with the body and truck bolsters thereof, which is self-centering through co-operating means on the body and truck bolsters and which is movable with said bolsters.

A more specific object of the invention is to provide a bearing member of the character indicated, including an anti-friction rolling element co-operating with opposed bearing members on the body and truck bolsters of railway cars providing crossing guideways controlling the position of the anti-friction element during its movement in the different angular positions assumed by the bolsters and acting to center said element when the bolsters are brought into aligned relation.

Other and further objects of the invention will more clearly appear from the description and claims hereinafter following.

In the drawing, forming a part of this specification, Figure 1 is a transverse section al view through the underframe structure of a railway car, showing portions of the body and truck bolsters in elevation and illustrating my improvements in connection therewith. Figure 2 is a top plan view of the truck 30 bolster member illustrated in Figure 1, showing the lower member of my improved side bearing in connection therewith. And Figure 3 is a longitudinal, vertical, sectional view through the bearing member illustrated in Figure 2, corresponding substantially to the line 3—3 of said figure.

In said drawings, 10 indicates a portion of the body bolster of a railway car and 11 the upper portion of the co-operating truck bolster. The center bearing member, about which the bolsters pivot, is indicated by 12 and is of the usual form.

My improved side bearing comprises, broadly, two housing members A—A and an anti-friction rolling element B.

The housing members A are of similar design and, as shown, one of the same is secured to the bottom side of the body bolster, while the other is secured to the top of the truck bolster. Each housing is in the

form of a casting having a main body portion 13 provided with laterally extending securing lugs 14—14 on the opposite sides thereof. The securing lugs are so arranged that two of the same are disposed on one side of the body member, while a central lug is disposed on the opposite side. The body portion 13 of each housing A is provided with spaced parallel side walls 15—15 forming a guideway therebetween. As shown, the side walls are 60 connected by curved end walls 16—16.

In the present instance, the anti-friction element B is shown as of the ball bearing type, and the bottom wall of the housing which sustains the thrust of the anti-friction element 65 is curved so as to correspond with the contour of the ball bearing member B. The side walls 15, as well as the end walls 16, also present curved surfaces which co-act with the ball member.

As clearly illustrated in Figure 1, the base portion of the housing A, which is secured to the body bolster, is inclined so as to properly fit the inclined bottom face of said bolster.

As shown in Figure 2, the two housings A are so arranged that the guideways, defined by the side walls, cross each other in such a manner that the ball B is confined by the side walls 15 to definitely position the same within the guideway between the side walls 15 of the other housing. In Figure 2, the position of the housing A, secured to the body bolster, is indicated in dotted lines and this position is assumed when the body and truck bolsters are vertically aligned.

In order to prevent clogging of the bearing member, the bottom housing A, which is secured to the truck bolster, is provided with clearing openings 17—17 at the opposite ends thereof, through which cinders and other foreign matter, which otherwise would accumulate in the bearing, is discharged.

The operation of my improved anti-friction bearing is as follows: When the body and truck bolsters are swung angularly with respect to each other about the center bearing member 12, the two housings will be displaced with respect to each other, and the anti-friction element B, which is confined between the spaced parallel side walls 15 of each housing, 100

will be guided along the guideways between the side walls 15 of said housings and maintained in a definite predetermined position. Upon swinging movement of the body bolster in an upward direction, as viewed in Figure 2, the ball member B will travel outwardly in both guideways of the housings A simultaneously until the outer end walls 16 of these guideways limit the movement of the ball.

10 Upon movement of the body bolster 10 in a reverse direction with respect to the truck bolster 11, the ball B will travel inwardly in both of the guideways of the housings A until movement thereof is arrested by contact with the corresponding end walls 16.

15 It will be evident that when the bolsters 10 and 11 are returned to their aligned position, the ball will be forced to travel back to the centered position shown in Figure 2.

20 While I have herein shown and described what I consider the preferred manner of carrying out my invention, the same is merely illustrative and I contemplate all changes and modifications which come within the scope of 25 the claims appended hereto.

I claim:

1. In an anti-friction side bearing for railway cars, co-operating with the body and truck bolsters thereof, the combination with 30 an anti-friction element disposed between said bolsters and adapted to roll with reference to the same; of means on each bolster by which said element is guided in a definite linear path with respect to said bolster and out 35 of alignment with the linear path of movement of said element on the other bolster, both of said guide means simultaneously and continuously engaging the anti-friction element during all operative positions of relative 40 swiveling movement of the bolsters and said guide means of each of said bolsters engaging the anti-friction element on opposite sides and cooperating with the guide means on the other bolster to control the position of said 45 element with respect to both bolsters during the relative angular movement of the bolsters and to center the same when said bolsters assume aligned relation.

2. In an anti-friction side bearing for 50 railway cars, co-operating with the body and truck bolsters of the car, wherein the bolsters are relatively movable to each other about a central pivotal axis, the combination with an anti-friction element interposed between said 55 bolsters having rolling contact therewith; and guide means on one of said bolsters continuously co-operating with said element, confining the movement of said element to a definite linear path with respect to said bolster and 60 means on the other bolster embracing said element on opposite sides for moving the same along said guideway when the bolsters are moved about their pivotal axis, the guide means on said bolsters extending in different 65 directions.

3. In an anti-friction bearing for railway cars, adapted to co-operate with bearing surfaces on the body and truck bolsters thereof, the combination with an anti-friction element interposed between said bolsters and having 70 rolling movement on the bearing surfaces of said bolsters; of means on said bolsters simultaneously and continuously co-operating with said element, the means on each bolster having constant engagement with said element 75 confining the same to movement along a definite path with respect to said bolster and engaging said element to move the same along the other bolster to control the position of said element along its path of movement with respect to the last named bolster, during swinging movement of said bolsters with respect to each other, when contact is broken between the anti-friction element and the bearing surface of the body bolster. 80

4. In an anti-friction bearing for railway cars, co-operating with the body and truck bolsters thereof, the combination with a member fixed to each bolster, presenting a bearing surface and spaced parallel guide 90 walls, the spaced guide walls of the opposed members being disposed at an angle to each other; of an anti-friction element interposed between the bearing surfaces of said members and having rolling contact therewith, 95 said anti-friction element being confined between the parallel side walls of both of said members, whereby the position of said element along its path of movement is controlled during relative movement of the body 100 and truck bolsters.

5. In an anti-friction bearing for railway cars, co-operating with the body and truck bolsters thereof, the combination with a support fixed to each bolster, said supports presenting opposed bearing surfaces; of an anti-friction element having rolling contact with said bearing surfaces; a guideway on each member formed by spaced parallel guide walls between which said element is confined, the guideways of said member extending in different directions, one across the other, whereby the position of the anti-friction element in said guideways is definitely controlled during relative movement of said 105 bolsters and centered when said bolsters assume a vertically aligned position.

6. In an anti-friction bearing for railway cars provided with body and truck bolsters, the combination with a housing secured to each bolster, said housing having spaced parallel side walls forming a guideway; of an anti-friction element having rolling movement, said element having engagement with 110 the opposed side walls of both of said housings and being confined thereby, the guideways of said housings being angularly disposed with reference to each other in crossing relation, whereby the movement of said 115

element is definitely controlled during relative angular movement of the bolsters.

7. In an anti-friction bearing for railway cars having body and truck bolsters swingable angularly with respect to each other, the combination with a housing secured to each bolster, said housing having a bearing surface and spaced parallel guide walls defining a guideway therebetween, the guideways of said housings crossing and deviating with respect to each other; of an anti-friction rolling element interposed between said bearing surfaces and confined between the parallel guide walls of both housings.

15 8. In an anti-friction bearing for railway cars having opposed body and truck bolster members, the combination with a bearing element fixed to each bolster, each of said elements being provided with a guideway, the 20 guideways of said elements deviating with respect to each other; of an anti-friction element having rolling movement on said bearing elements and constantly engaging in and fitting the guideways of both of said bearing 25 elements to confine the anti-friction element against lateral movement with respect to the guideway of each bolster.

9. In an anti-friction bearing for railway cars provided with opposed body and truck 30 bolsters, the combination with a bearing member secured to each bolster, said bearing members presenting opposed bearing surfaces, each bearing member having spaced parallel side walls defining a guideway there- 35 between, said guideways extending in different directions and crossing each other; of an anti-friction ball bearing interposed between the bearing surfaces of said guideways, said ball bearing engaging between the spaced 40 side walls of both of said bearing members and being confined against lateral displacement with respect to the guideway of each of said bearing members by the side walls thereof.

45 In witness that I claim the foregoing I have hereunto subscribed my name this 10th day of May, 1928.

JOHN F. O'CONNOR.
